STRIP SHINGLE

Application filed May 4, 1929. Serial No. 360,374.

This invention relates to roofing elements or shingles and more particularly to an improved form of flexible composition roofing strip of the type wherein notches or recesses 5 are utilized to define tabs simulating separate shingles when a number of the strips are laid on a roof.

Perhaps the most common form of roofing strip now used is that wherein narrow notches 10 or slots are formed in the weather-exposed area to define shingle-simulating tabs. These strips, as is well known, are laid up on the roof in successive overlapping courses with the adjacent strips of each course arranged side by side and with the overlapping strips of each course in staggered relation with respect to the strips of the preceding course. When shingles of this type are thus arranged on a roof, the slots or notches necessarily expose a corresponding area of the normal concealed or overlapped portions of the underlying strip, and water seeping or blowing in under the strips, especially near the upper ends of the slots, is very liable to 20 reach the roof supporting structure unless the strips are sufficiently wide to underlap the shingles of the succeeding course for a considerable distance beyond the upper ends of the slots therein.

The principal object of my invention resides in the formation of shingle strips in such a manner that the tab-defining slots thereof are sealed or closed off so as to avoid the possibility of water gaining entrance beneath the upper ends of the slots.

A further object of the invention is to provide strips with spaced extensions or flaps secured in folded position to the underface of the strips, in such relation to the tab-defining slots as to realize the principal object of the invention as aforesaid, and serving additionally, in many instances to increase the shingle-simulating effects of the slots.

Still a further object of the invention resides in so constructing the extensions that when they are in their underfolded position, the lower or butt-edge of the finished strips will be of greater thickness than usually obtains in the present commercial form of strips of this character, the increased thick-

ness lending the highly desirable shadow effects to a roof laid up with an assembly of such strips.

With the above and other objects in view, which will appear as the description proceeds, my invention consists in the novel construction, arrangement and combination of various elements and parts described in the following specification and illustrated in the accompanying drawings. While I have 55 illustrated and will describe certain preferred embodiments of the invention, it will be understood that such variations or modifications thereof may be made as will fall within the scope of the appended claims.

In the drawings:

Figure 1 is a plan view of one form of my improved shingle strip as it appears when severed from a sheet of roofing material and prior to completion of the strip,

Figure 2 is a similar view of the completed strip,

Figure 3 is a similar view showing the reverse or underface of the strip,

Figures 4 and 5 are transverse sections 75 along lines 4-4 and 5-5 respectively, of Figure 1,

Figure 6 is a similar section taken along lines 6-6 of Figure 2,

Figure 7 is a plan view similar to Figure 80 1, illustrating another form of the shingle strip, and

Figure 8 is a plan view of a sheet of roofing material, illustrating the manner of severing therefrom strips of the type shown in 85 Figures 1 to 6.

The strips, according to my invention, are formed of flexible water-resistant fibrous base, such as the ordinary asphaltic felt-base roofing fabricated from sheets of rag, asbestos or similar fibers. These sheets are rendered water-resistant by impregnating them with asphalt or the like, and one or both surfaces thereof are then supplied with a coating layer of weather resistant material such 90 as blown asphalt having a melting point approximately 220° F. Mineral surfacing such as crushed slate, is partially imbedded in the coating layer on the surface to be exposed on the roof, and when the opposite surface of 100

the sheet also has a layer of coating, the latter is generally provided with a surfacing of fine mineral such as talc or mica.

As shown, the main body portion of the shingle is indicated generally by the numeral 10 and comprises an upper portion 11 which is the unexposed or concealed part of the strip when laid, and a lower or weather-exposed area 12. The exposed portion 12 is formed with shingle-simulating tabs 13 defined from each other by spaced vertical slots 14, which are preferably made in the sheet at an appropriate stage of its fabrication prior to the severance of the separate strips from the sheet. The tab-defining slots 14 may be spaced apart at equal distances as shown, so as to provide shingle-simulating tabs of equal width, or they may be spaced apart at variable distances as shown in dotted lines, so that the tabs will be of varying widths. The line of exposure of the strips will be defined by the upper ends of the slots 14, whereas the lower or butt edge of the elements may be on a horizontal line adjacent the lower extremities of the slots. At the lower margin of the exposed portion of the strip, I form a series of extensions or projections 15, 15', the terminal extensions 15' being substantially half the width of the inner extensions 15 and the intervening spaces 16 between the several extensions of the series being substantially complementary to the extensions 15.

In order to realize the advantages of my invention, it is necessary that the vertical side edges of each flap or extension 15, 15' be spaced laterally from the vertical side edges of a corresponding tab-defining slot 14 as contradistinguished from substantial vertical alignment therewith.

Strips of the type shown in Figure 1 may be severed from a sheet of prepared roofing in the manner illustrated in Figure 3. As will be noted from this figure, the sheet is of a width sufficient to form a double series of strips transversely thereof. The tab-defining slots 14 are formed in the sheet in two spaced rows, the slots of each row forming the tab-defining slots of the respective series of strips. The slots of each row are formed at suitably spaced intervals and preferably, the slots of one row are offset or staggered with respect to the slots of the other row, as shown. The projections 15, 15' of the strips are formed in the portions of the sheet intermediate the two rows of slots, by a series of alternately longitudinal and transverse cuts 20, 21 respectively, so that the material forming the projections of one series of strips leaves the complementary areas forming the spaces 16 between the projections on the strips of the other series formed from the sheet. In this way, therefore, the strips may be severed from the sheet by a simple cutting operation without waste. The strips of each series may

be severed from the two sections of the sheet formed by the cuts 20, 21, by severing each of these sections along spaced transverse cuts 22, as shown.

After the strips are thus severed from the sheet, they are folded on a horizontal line, as indicated at X in Figure 1, preferably slightly above the lower extremities of the slots 14, so as to bring the lower face of the extensions 15, 15', into contact with the lower face of the exposed portion of the strips, the vertical length of the extensions being such that when thus folded the lower margins 17 thereof will be positioned on a line slightly above the upper ends of the slots 14. I prefer to unite the extensions 15 with the main body portion of the strips in any convenient way, as for example, by means of adhesive material, such as asphalt, applied to these areas prior to the folding operation, after which the folded areas may be passed through pressure rolls and the asphalt allowed to cool so as firmly to unite the extensions in their underfolded position with the lower face of the body portion, as shown in Figure 6. If desired, the flaps may be brought to retroverted position and left unattached to the underface of the shingle, in which case the securing nails for the shingles, when driven therethrough in applying the shingles to the roof, will pass through the extensions and serve to retain them in proper position.

As clearly illustrated in Figures 2, 3 and 6, the underfolded projections 15, serve as closures to seal off the lower face of the slots 14 so that when a number of strips are assembled in proper position on a roof, there will be no tendency for water or rain to creep or drive up under the upper ends of the slots 14 and reach the roof deck. Where the extensions or flaps 15 are of sufficient width, the tab-defining slots may be spaced from each other at unequal distances as shown in dotted lines in Figure 1 so as to provide shingle-simulating tabs of a variable width, the essential requirement being that the slots be arranged not less than a certain minimum distance from the vertical side edges of the extensions 15. In actual practice, for example, with a strip as shown in the figure which is 36" in length, the extensions 15 will be about 6" wide and the position of the slots 14 may vary over a horizontal distance of 4" as long as they are confined to at least 1" inwardly of the vertical side edges of the flaps 15.

As an important feature of the construction provided by my invention, it will be observed that where the upper surface of the sheet is finished with crushed mineral grit of suitable light color, and dark colored mineral grit is affixed to the underface of the sheet, or left unsurfaced, so as to leave a substantially black or dark colored appearance thereon, this dark color of the lower face of the sheet being visible through the

slots 14 of the completed strip, will greatly accentuate the individual shingle-simulating effect of the slots. Furthermore, when the strips are applied on the roof, water that 5 may collect in the channel formed by the tab-defining slots and the underlying flap 15, will pass downwardly under the influence of the natural pitch of the roof and drain through the small openings 18 at the lower 10 ends thereof, onto the surface of the sub-adjacent strip. Accordingly, instead of the usual construction wherein water may creep or be blown up under the shingles through the tab-defining slots, I provide by my invention 15 a construction in which a definite sealed path forms a positive drain for water reaching and collecting in the slots.

Still further, it will be noted that in the folded and completed form of the shingle a 20 comparatively thick edge is presented at the lower margin thereof, thus enhancing the shadow effects produced by the butt-edges of the shingles when laid on the roof.

Shingle strips constructed in accordance 25 with my invention also afford certain advantages when subjected to a recoating and resurfacing operation of the type set forth in the Patent Number 1,612,776, to Lester Kirschbraun. In accordance with the said 30 patent shingles or shingle strips are subjected to reimmersion in asphaltic coating material in order to encase the weather exposed surfaces and edges of the shingle elements in a protecting layer of weatherproof material, the recoated areas being also preferably surfaced with crushed mineral of a suitable variety. In the practical manufacture 35 of strips in accordance with the said Kirschbraun patent, the treatment provided by said 40 patent is generally reserved for shingle "seconds", that is to say, shingles as ordinarily produced but which carry slight imperfections or irregularities which do not perceptibly affect the life of the shingle and which 45 are objectionable only from the viewpoint of appearance. The recoating and resurfacing operation accordingly provides an effective means for reclaiming shingle "seconds" and 50 converting them into a more desirable type of shingle, this being advantageous also from the standpoints that the exposed surfaces and edges are sealed against the action of the elements, and further that the recoated and resurfaced elements present an increased 55 thickness of highly desirable texture along the butt edges thereof.

In thus reclaiming shingle "seconds", it 60 frequently happens that the shingle to be retreated is of a light color and the mineral surfacing used in the retreating operation is of a dark color. In these cases, therefore, when the retreated shingles are laid upon the roof, the light color of the upper portion of 65 the shingles, (the retreating operation not being applied to these portions), is visible

through the slots of the overlying shingles and this is frequently objectionable and heretofore has been overcome only by a careful and tedious selection of the color of the shingles to be retreated in accordance with the color of the mineral to be used in the retreating operation. In the shingle strips as provided by my invention, on the other hand, the flaps 15 conceal the mineral surfacing on the upper portions of the underlying strip, and hence shingles constructed in accordance with my invention, may be retreated in accordance with the said Kirschbraun patent without reference to their original color. 70 75 80

The shingle strip construction of my invention also affords certain advantages in connection with the production of shingles, the exposed areas whereof are formed with a layer of copper by electrodeposition. In the actual practice of electrodeposition copper on mineral surfaced prepared roofing shingles, the deposition of copper is confined substantially to the areas to be exposed, as otherwise the cost would be prohibitive. In 85 electrodepositing copper upon shingles of the square-butt variety it is necessary to deposit the copper not only upon the lower portions of the shingles which form the weather-exposed areas thereof, but also to form an electrodeposited tongue of copper on the upper portions of the shingle intermediate the tab-defining slots, so that when the shingles are applied in courses on the roof, these tongues of copper will underlie the slots and be visible therethrough. The electrodeposition of these separate tongues extending into the upper areas of the shingles, involves a rather sensitive operation in commercial practise and represents a costly element of the manufacture. The necessity for thus plating the 90 tongues of copper may be avoided with shingles constructed in accordance with my invention, for, as will be noted, when the lower or weather-exposed areas 12 of my strip shingle are made electroconductive, and then passed through an electroplating bath, the copper will be deposited not only upon the surface of the tabs 13, but also upon the surfaces of 95 the projections 15 which are exposed through the slots 14, so that when these electroplated copper shingles are applied on the roof, the entire visible exposed surface will carry the copper coating and hence there is no necessity 100 for plating tongues of copper in the upper 105 areas of the shingle as heretofore. 110 115 120

In Figure 7 of the drawings, I have shown a slightly modified construction of my invention wherein the flaps or projections 19, 19', which are to be folded under and secured to the main body of the shingle, are of generally semi-hexagonal instead of rectangular shape. Except for this variation in the shape of these projections, however, the shingle strip as shown in Figure 7 embodies every 125 130

feature of my invention, as heretofore described, as will be apparent to those skilled in the art.

If desired, in some instances the tab-defining slots 14 of Figures 1 to 6 may be inclined somewhat to the vertical, instead of being perpendicular to the butt-edges of the strips, within the limits prescribed for the distance between the slots and the side-edges of the flaps or projections 15, 15'.

Having thus described my invention, it will be understood that numerous changes and modifications may be made therein without departing from the spirit of the invention as defined in the subjoined claims.

I claim as my invention:

1. A shingle comprising a body portion formed with spaced tab-defining slots in the lower or weather-exposed areas thereof, and integral extensions spaced from each other by intervening recesses complementary to the extensions, whereby the shingles may be cut from a parent sheet without waste, said extensions being fixedly united to the underface of the body portion and arranged to substantially completely underlie said slots.

2. A roofing element comprising a body portion formed with spaced tab defining slots in the lower or weather exposed area thereof, and integral extensions spaced from each other by intervening recesses in such manner as to enable the elements to be cut from a parent sheet without waste, said extensions being retroverted to substantially completely underlie said slots.

Signed at Rutherford in the county of Bergen and State of New Jersey this third day of May A. D. 1929.

JULES L. WETTLAUFER.
